UNITED STATES PATENT OFFICE.

FRANK FOURT, OF FAIRFIELD, IOWA.

BLOW-OUT HOLDER.

1,075,347.

Specification of Letters Patent. Patented Oct. 14, 1913.

Application filed September 7, 1912. Serial No. 719,253.

To all whom it may concern:

Be it known that I, FRANK FOURT, a citizen of the United States, residing at Fairfield, in the county of Jefferson and State of Iowa, have invented certain new and useful Improvements in Blow-Out Holders, of which the following is a specification.

This invention relates to blow-out holders for pneumatic tires and has for its object the production of an efficient holder which may be readily secured around the inner tube of a tire and prevent its being forced through any weak place or opening in the outer casing, by the air pressure from within.

Another object of this invention is the production of an efficient blow-out holder which may be so secured around the inner tube of the tire to prevent the inner tube from becoming injured or wearing along the edge of the blow-out holder.

With the above and other objects in view as will be hereinafter apparent the invention consists in general of certain novel constructions, combinations and arrangements of parts, as will be hereinafter fully described, illustrated in the accompanying drawings, and specifically claimed.

In the drawings:—Figure 1 is a bottom plan view of the bandage. Fig. 2 is a section on the line 2—2, Fig. 1. Fig. 3 is a section taken on the line 3—3, Fig. 1. Fig. 4 is a transverse sectional view through the bandage showing the same in its stretched out condition. Fig. 5 is a transverse section through a tire showing the bandage positioned upon the inner tube. Fig. 6 is a fragmentary longitudinal section through a tire showing the manner in which the bandage fits upon the inner tube. Fig. 7 is a plan view of the blank from which the bandage is made. Fig. 8 is a detail perspective of one end of the bandage.

By reference to the drawings, especially Fig. 7, it will be seen that the blow-out holder is formed from a blank sheet of fabric or other desirable material 1 and comprises a widened flap end portion 2, a central narrowed intermediate portion or portions 3, and an outer end portion 4, which outer end portion is slightly wider than the central portion or portions 3 and slightly narrower than the outer flap 2. Said portions 2, 3, and 4 vary in length, 2 being longer than 3 and 3 longer than 4.

After the blank is cut in the form as illus-

trated in Fig. 7 the end portion 4 is folded back upon the intermediate portion 3 and the two flaps 3 and 4 are then folded over upon the flap end 2, the end portion 4 being placed between the intermediate portion 3 and the flap end 2. These portions 2, 3, and 4 being folded as above described, the blow-out holder is stitched longitudinally thereof as indicated by the numeral 5, in Fig. 4.

A plurality of eyes 6 are formed adjacent the edges of the blow-out holder through which eyes are adapted to pass the lacing 7 for firmly binding the blow-out holder around the inner tube as is illustrated in Fig. 5. A portion of the flap end 2 projects beyond one side of the blow-out holder thereby constituting a sealing flap 8. This sealing flap is adapted to fit under the joint of the two sections of the blow-out holder as illustrated by the numeral 9, in Fig. 3.

By having the different portions 2, 3 and 4 formed of different widths it will be seen that as the flaps are folded a tapering end will be formed upon each end of the blow-out holder as indicated by the numeral 10, in Fig. 2. By having this structure it will be seen that no rib portions will be presented upon each end of the blow-out holder as is now usually the case but the slightly tapering ends will gradually conform to the inner tube in such manner as to prevent injury to the inner tube and prevent cutting thereof along the edge of the blow-out holder.

From the foregoing description it will be seen that a very efficient bandage or blow-out holder has been produced which can readily and quickly be secured around the inner tube of a tire to be placed opposite a weak spot or blow-out in the outer case so as to form an efficient seal over a portion of the outer case which is punctured or otherwise injured. It will be further obvious that a blow-out holder has been produced which will conform to the contour of the tire in such manner as to prevent wearing of the blow-out holder upon the inner tube as to cause the tube to become worn or injured.

What is claimed is:

A blow-out holder of the class described formed from a blank of material comprising a main flap, an intermediate narrower flap, and an outer flap wider than said intermediate flap and narrower than said

first mentioned flap, said flaps being folded so as to have said last-mentioned flap fit between said intermediate flap and said first-mentioned flap, said first-mentioned flap 5 extending beyond the edge of the other flaps and constituting a sealing cap for said blow-out holder as the same fits around the inner tube of a tire, the side edges of said flaps after the same have been folded being provided with eyelets, said flaps being stitched

together along the adjacent ends of said blow-out holder, and lacing means passing through said eyelets for securing the blow-out holder around the inner tube of a tire.

In testimony whereof I hereunto affix my 15
signature in presence of two witnesses.

FRANK FOURT.
